TONE ARM

Ford William Schmid, Conneaut, Ohio, assignor to The Astatic Corporation, Conneaut, Ohio, a corporation of Ohio

Application October 6, 1955, Serial No. 38,270

Term of patent 7 years

(Cl. D26—14)

Figure 1 is a front perspective view of a tone arm showing my new design;

Figure 2 is a top plan view of the tone arm of Figure 1;

Figure 3 is a side elevation of the tone arm of Figure 1; and

Figure 4 is an end elevation of the tone arm of Figure 1.

I claim:

The ornamental design for a tone arm, as shown.
